(57) **CLAIM**

The ornamental design for a profile for a hinged container wall, as shown and described.

DESCRIPTION

FIG. 1 is a front, right perspective view of the profile for a hinged container wall showing my new design;

FIG. 2 is a right side view of the first embodiment of the profile for a hinged container wall of FIG. 1;

FIG. 3 is a front view of the first embodiment of the profile for a hinged container wall of FIG. 1; and,

FIG. 4 is a bottom view of the first embodiment of the profile for a hinged container wall of FIG. 1.

The broken lines immediately adjacent to the shaded areas represent the bounds of the claim and all other broken lines showing the remainder of the profile are for the purposes of illustrating the environment. None of the broken lines form a part of the claimed design.
